UNITED STATES PATENT OFFICE.

STANLEY KRAWCZYK AND ADOLF KÖNIG, OF PLAINFIELD, NEW JERSEY.

LOOM SHUTTLE.

1,416,095.

Specification of Letters Patent. Patented May 16, 1922.

Application filed May 3, 1921. Serial No. 466,544.

To all whom it may concern:

Be it known that we, STANLEY KRAWCZYK and ADOLF KÖNIG, citizens of the United States, and residents of Plainfield, in the county of Union and State of New Jersey, have invented certain new and useful Improvements in Loom Shuttles, of which the following is a specification.

The present invention relates to improvements in loom-shuttles, and has for its main object to provide a shuttle with a simple and inexpensive means which prevents longitudinal motion of the cop on the shuttle spindle when the latter is in its operative position, but permits of such movement when the said spindle is in its open or raised position.

Another object of the invention is to so construct and arrange the means which prevents the cop from longitudinal movement on the spindle that the same does not interfere with the proper operation of the shuttle.

A further object of the invention is to make the shuttle spindle expansible and to mount thereon a mechanism which will increase its size when the said spindle is shifted from its raised position into the shuttle, its size being automatically reduced when moved to raised position.

A still further object of the invention is to so construct the means which prevents the cop from longitudinal movement on the spindle that it may be conveniently mounted on already existing structures, without necessitating material changes in the construction of the latter.

Another object of the invention is to provide a shuttle of the type mentioned which is capable of manufacture on a commercial scale, or in other words one which is not so difficult to make as to be beyond the reasonable cost of such a contrivance.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

One of the many possible embodiments of the invention is illustrated in the accompanying drawings, in which:

Figure 1 is a side elevation, partly in section, of a shuttle constructed in accordance with the present invention; Fig. 2 is a section taken on line 2—2 of Fig. 1; Fig. 3 is a view similar to the one shown in Fig. 1 of the drawings with the elements in other positions; and Fig. 4 is a section taken on line 4—4 of Fig. 3.

In the drawings, the numeral 10 indicates a shuttle body of any suitable configuration and type. This body is provided with a longitudinal opening 11, receiving the cop 12, shown in dotted lines in Figs. 3 and 4 of the drawings, said cop being wound upon a cop tube 13, the latter being drawn over the spindle 14. The spindle is pivoted at 15 to the shuttle body and with the same co-operates a spring 16, to hold it in both its normal and raised positions, shown in Figs. 1 and 3, respectively, of the drawings. The pivoted end 17 of the spindle is enlarged, as clearly shown in the drawings, and provided in its underface with a notch 18, adapted to receive a transverse pin 19 on the shuttle body, said pin extending in parallel relation to the pivot pin 15. The notch and pin 19 determine the depressed position of the spindle, the raised position thereof being determined by a stop 20 on the shuttle body, against which the enlarged end 17 of the spindle is adapted to abut, as shown in Fig. 3 of the drawings. The construction of the elements thus far described is of the usual type and their functions and operations are well known.

Through the spindle 14 extends a longitudinal slot 14' which makes the spindle expansible. In the said slot is disposed an abutment 21, having a wedge-shaped end 22 facing the pivot pin 15. This abutment is made in the form of a, preferably, metallic strip, held in position on the spindle by a screw 23, which extends through a slot 24 in the spindle, the slot 24 extending in a plane at right angles to that of the slot 14'. The slot 24 permits of an adjustment of the abutment on the spindle, for a purpose hereinlater to be described. The head 25 of the said screw is disposed within a recess 26 in the spindle, so as not to interfere with the mounting of the cop thereon. To hold the abutment fixed in position upon the spin-

dle, the same is provided with serrations 27, co-operating with serrations 28 on the spindle. With the said abutment co-operates a pin 29, that is longitudinally movable within a bore 29' in the slot 14', it being pivotally connected to a lever 30, which extends partly into the slot 14' and bore 29'. This lever is mounted on the pin 19 above referred to. The pin 29 and abutment 21 are wholly disposed within the spindle, the free end of the pin 29 being wedge-shaped, as shown at 32, said wedge-shaped end being adapted to ride over the wedge-shaped end 22 of the abutment. As appears from the drawings the pin 19 is disposed below the pivot pin 15 between the latter and the abutment 21.

The outer face of the spindle 14 is provided with teeth 33, for engagement with the inner face of the cop tube 13.

The operation of this device is as follows: When the elements are in the positions shown in Figs. 3 and 4 of the drawings, that is to say when the spindle is swung around its pivot 15 so as to be disposed outside of the opening 11, the pin 29 is disengaged from the abutment 21, the result being that the spindle assumes its normal size. The operator draws then the cop over the spindle, bringing the cop tube against the enlarged portion 17 of the said spindle. When now the spindle, with the cop thereon, is depressed, that is to say is swung around its pivot pin 15 into the opening 11 in the shuttle body, the lever 30 swings in the same direction on the pin 19, with the result that the pin 29 is caused to move toward the abutment 21, riding over the wedge-shaped end 22 of the latter and thus expanding the spindle. The result of this expansion is that the cop is firmly held in position upon the spindle both against turning and longitudinal movements. The amount of expansion of the spindle is determined by the position of the abutment in relation to the pin 29. When the spindle is raised, the pin 29 automatically recedes from the abutment, whereby the size of the spindle is reduced, thus permitting of a convenient removing of the empty cop tube therefrom. The size of the cop tube is, obviously, such that it may be easily drawn over the spindle, when the latter is in its raised position.

Attention is called to the fact that, inasmuch as the abutment may be adjusted in relation to the pin 29, the shuttle is adapted for use in connection with different sizes of cops. It is to be noted that the cop tube abuts against the enlarged portion 17 of the spindle. For this reason the thread or yarn cannot, in the operation of the shuttle, come between the cop tube and the said enlarged spindle portion, there is no possibility thus of the thread or yarn being torn,

as in the constructions heretofore in use, in which the spindle usually has to be made larger than the bore of the cop tube in order to hold the cop in position, and consequently the cop tube cannot be brought into abutment with the enlarged portion of the spindle.

The device herein described has a number of advantages over the old constructions. In the devices heretofore used considerable time is wasted in placing the cops into the shuttles and besides that the operation requires quite some strength on the part of the operator. No matter how tight the cops are put on and no matter how careful the operator is in doing this work, the cops shift on the spindles, the result being that the filling or yarn is apt to break. This not only means loss of time, stopping of the loom, etc., but also a waste of the filling or yarn. Inasmuch as in the constructions heretofore used, the cop must be forced onto the spindle, the latter is often bent and the shuttle body split. With the device herein described these troubles are all overcome. Moreover, such cops, in which the thread or yarn is too loosely wound upon the cop tubes, are adapted for use, because the cop is expanded when the spindle size is enlarged. In the constructions heretofore in use this is not the case. As a matter of fact, through the squeezing and twisting, to which the cop is subjected in putting the same on the spindle, the thread or yarn is even more loosened up, so that, when the shuttle is put in motion, the entire cop comes off at once, resulting in waste of material and time.

It is to be observed that the lever 30 and pin 29, in co-operation with the abutment 21, act as a brake for the spring 16. When, therefore, the spindle is shifted from its raised position into the shuttle body, the spindle has no tendency to bend the pin 19 and possibly split the shuttle body.

What we claim is:

1. The combination with a shuttle body having an opening, of an expandible spindle pivoted thereto adapted to receive a cop, an abutment fixed within said spindle having a wedge-shaped end facing the pivot of said spindle, a longitudinally shiftable pin wholly disposed in said spindle and adapted to co-operate with said abutment, and a lever pivoted to said body and connected with said pin, said lever swinging with said spindle and causing said pin to ride over the wedge-shaped end of said abutment when said spindle is swung into said opening and withdrawing said pin from said abutment when said spindle is raised out of said opening.

2. The combination with a shuttle body having an opening, of a split spindle pivoted thereto adapted to receive a cop, a lever pivoted to said body, and means wholly disposed within said spindle and connected to

said lever for causing an expansion of said split spindle when the latter is swung into said opening and causing a contraction thereof when said spindle is raised out of said opening.

3. In a shuttle according to claim 1, said abutment being adjustably fixed to said spindle to predetermine the extent of expansion thereof.

10 4. In a shuttle according to claim 1, the free end of said pin being also wedge-shaped.

5. The combination with a shuttle body having an opening, of an expansible spindle pivoted thereto adapted to receive a cop, the 15 pivoted end of said spindle being enlarged and having a notch in its under-face, a stop-pin on said body adapted to receive said notch, an abutment fixed within said spindle having a wedge-shaped end facing the pivot 20 of said spindle, a longitudinally shiftable pin wholly disposed within said spindle and

adapted to co-operate with said abutment, and a lever fulcrumed to said stop-pin and connected with said shiftable pin, said lever swinging with said spindle and causing said shiftable pin to ride over the wedge-shaped end of said abutment when said spindle is swung into said opening and withdrawing said shiftable pin from said abutment when said spindle is raised out of said opening.

10 6. In a shuttle according to claim 5, said abutment being adjustably fixed to said spindle to predetermine the extent of expansion thereof.

7. In a shuttle according to claim 5, the 35 free end of said shiftable pin being also wedge-shaped.

Signed at Plainfield, in the county of Union and State of New Jersey, this 18th day of April, A. D. 1921.

STANLEY KRAWCZYK.

ADOLF KÖNIG.
